UNITED STATES PATENT OFFICE.

JOHN L. LINCOLN, OF CHICAGO, ILLINOIS.

CLOTHES-DRIER.

SPECIFICATION forming part of Letters Patent No. 435,436, dated September 2, 1890.

Application filed December 23, 1889. Serial No. 334,611. (No model.)

To all whom it may concern:

Be it known that I, JOHN L. LINCOLN, a citizen of the United States, and a resident of Chicago, county of Cook, and State of Illinois, have invented new and useful Improvements 5 in Clothes-Driers, of which the following is a specification, reference being had to the accompanying drawings, illustrating the invention, in which—

10 Figure 1 is an end elevation of my improved clothes-drier as suspended from a ceiling and in position for use, its position when moved to one side and elevated being shown by dotted lines; Fig. 2, a plan view of the line-frame and operating-cords removed from the 15 hanger-rods.

The purpose of this invention is to provide 20 means for moving the line-frame of a clothes-drier from one part of a room to another part and by the same means to elevate the frame 25 when required. Two rods A are suspended a short distance from and parallel with the ceiling by three hangers B each. These rods are placed a distance apart corresponding to 30 the width of the line-frame D E and pass through the heads of the hangers B, which, by means of screw-threads, are turned into 35 the ceiling such a distance apart as the line-frame is long, measuring on the rods. The frame is rectangular, and is formed of two long bars E E and two shorter bars D D. Four flexible hangers C are respectively attached to the four corners of the frame, and their ends are provided with rings b, which 40 are strung on the rods A, so that the hangers C at each side of the line-frame shall be supported by a single rod, and so that a ring shall be placed on each side of the middle hanger B. This is done that the line-frame may be

40 moved its length without being elevated, and so that when the line-frame is to be elevated the rings of the two front line-hangers will be stopped by the two left-hand hangers B. Cords a a, &c., are at their ends attached by ordinary means to the ends D of the line-frame, and on them the clothes are to be hung, and cords F F are attached to those 45 corners of the line-frame most remote from the pulley K, and they are united with a single cord G at a point near the left-hand portion of the line-frame, and cords J I are respectively attached to those corners of the line-frame nearest to the pulley K, and they are united with a single cord H far enough 50 from the frame to draw on its corners. The 55 cords G H run over a double pulley K, which is attached to the ceiling or other elevated place, and from thence extend down to within reach to be drawn upon to move forward the line-frame or to elevate it. The cords G H 60 are to be fastened to any well-known device to hold the line-frame elevated.

I claim as new and desire to secure by Letters Patent of the United States—

An improvement in clothes-driers, consisting 65 of the line-frame D E, provided with lines a a, &c., in combination with rods held parallel with the ceiling, flexible line-frame hangers C, provided with rings to slide on 70 said rods, and forked cords attached to the four corners of the line-frame and terminating in two cords running over a double pulley attached to the ceiling or other convenient place at one side of the line-frame, as specified.

JOHN L. LINCOLN.
